MAGNETRON OUTPUT COUPLING SYSTEM

Albert M. Clogston, New York, N. Y., and Alexander G. Smith, Durham, N. C., assignors, by mesne assignments, to the United States of America as represented by the Secretary of War

Application June 21, 1946, Serial No. 678,240

10 Claims. (Cl. 315—39)

1

This invention relates generally to magnetron oscillators, and, more particularly, to means for extracting oscillatory energy from such devices.

In the generation of hyper-frequency oscillations, the magnetron-type electron discharge device has proved exceptionally useful. This tube is capable of generating centimeter waves at power levels of kilowatts. At the shorter of the wavelengths which are in common use, it is most convenient to employ wave guide energy transmission systems in conjunction with the magnetron oscillator in order to reduce power losses to a minimum. However, in the past, the most readily practicable means of coupling energy from a magnetron to a transmission system has been found to be a section of coaxial line, the center conductor of which projects into the magnetron shell in the form of a small loop or probe. It can be seen that, if such output coupling is used, there must needs be another coupler between the coaxial section and the wave guide line. The disadvantages of this type of system are numerous. The losses introduced by the coaxial line are appreciable; the couplers are not 100 per cent efficient and the losses therein are multiplied by the number of such coupling devices; and a coaxial line is not capable of handling as high power as is a wave guide, hence a limitation is put on the peak power which the entire system can handle. Furthermore, at the shortest wavelengths, the extremely small size of the magnetron and energy carrying components renders it difficult to fabricate a coaxial output.

Accordingly, it is one object of the present invention to provide means of coupling magnetron oscillators directly to a wave guide transmission line without the use of coaxial components.

Another object is to provide a magnetron output system capable of handling high oscillatory power.

Still another object is to provide magnetron output means which may be conveniently manufactured regardless of the frequency for which it is designed.

Briefly, the invention is embodied in a magnetron oscillator having a longitudinal slot in its outer shell. To this slot is attached a wave guide section which changes from a width approximately that of the slot to the width of the main wave guide. Probes, loops, or coaxial components are not necessary.

The principles and operation of our invention will be more apparent to those skilled in the art upon reference to the following specification and claims; and to the drawings in which;

Fig. 1 is a sectional plan view of a magnetron and wave guide coupler constructed according to the principles of my invention;

2

Fig. 2 is a longitudinal section through the magnetron and coupler of Fig. 1 along the line 2—2, omitting the cathode; and

Fig. 3 shows another type of coupler which may be used.

Referring now to Fig. 1, a horizontal section through a vane-type magnetron is shown. The principal components of this type of magnetron are the shell 5, vanes 6, and cathode 7. Vanes 6 partition the interior of the shell into individual resonant cavities. Electrons are emitted from cathode 7 and describe an orbital path about the cathode. As the electrons move past the entrance to each cavity, oscillations are set up within the cavity at a frequency chiefly determined by its physical dimensions. A relatively narrow slot 8 is cut through wall 5 into one of these cavities to allow egress of energy. Wave guide section 10 is attached to the magnetron by sealing its walls hermetically to magnetron shell 5. Since the width of slot 8 is much less than that of the main wave guide 9, the walls of guide section 10 taper smoothly to effect a transition in dimensions. The taper also has the effect of matching the impedance of the oscillator to that of guide 9 as will be elaborated hereinafter. A glass window 11 is sealed into the guide to allow evacuation of the magnetron tube. The precise location of the window is not critical, and it may be placed at whatever point in the wave guide is most convenient for its insertion.

Fig. 2 is a longitudinal section through the apparatus of Fig. 1 along the line 2—2 illustrating the height of slot 8 and the fact that the upper and lower walls of guide section 10 are parallel.

In general, the output impedance of the magnetron will not be the same as the input impedance of the main wave guide, hence there is the problem of matching these two impedances. It has been found that the ratio of the energy remaining within the magnetron anode to that propagated down the wave guide is substantially equal to the ratio of the impedance of the anode to that of wave guide 9 during each cycle of oscillation. Experimentation has shown that this ratio must be maintained within certain limits in order that the magnetron may act as an efficient generator of power. The tapered transition section provides a gradual transformation of impedances, since the impedance of each incremental length of wave guide is proportional to the width of the guide. The cut-off wavelength of the guide, being dependent only on the longer cross-sectional dimension of the guide (for the most commonly used $TE_{0,1}$ mode), is unaffected.

However, a tapered section is not the only means of impedance transformation possible, an-

other form being shown in Fig. 3. In this figure, the transition section 12 has parallel walls which are approximately one-quarter wavelength long. The quarter wavelength transformer is a means of impedance transformation well known in the art. It is particularly useful when matching between elements differing widely in impedance. In this case, it offers certain advantages in simplicity of construction over the tapered transition section shown in Figs. 1 and 2. However both forms of impedance transformation devices have been found practicable.

While there has been described hereinabove what are at present considered to be preferred embodiments of the present invention, it will be obvious to those skilled in the art that changes and modifications may be made therein without exercise of inventive ingenuity. Hence, all such modifications and adaptations are claimed as may fall fairly within the true spirit and scope of the invention.

What is claimed is:

1. In a hyper-frequency energy generation system, a magnetron electron discharge device having a source of electrons, said device having a plurality of cavity resonators symmetrically disposed about an axis, a rectangular wave guide, a transitional section of wave guide of rectangular cross-section having one end connected to said rectangular wave guide and its other end abutted against the outer wall of said magnetron and hermetically sealed thereto, a substantially rectangular passage being provided in the magnetron wall opening into the interior of said transitional section and one of the cavity resonators of said magnetron, said passage extending axially substantially the height of said cavity resonator and said transitional wave guide section and being appreciably narrower in width than said cavity resonator, said transitional wave guide section having a constant height in the axial direction.

2. The invention in accordance with claim 1 wherein there is progressive variation in the width of said transitional wave guide section.

3. The invention in accordance with claim 1 wherein in addition said transitional wave guide section is in length substantially one-quarter of a wavelength of the oscillatory energy contained therein.

4. In a hyper-frequency energy generation system, a magnetron electron discharge device having a source of electrons, said device having a plurality of cavity resonators symmetrically disposed about an axis, a rectangular wave guide, a transitional section of wave guide of rectangular cross-section having one end connected to said rectangular wave guide and its other end abutted against the outer wall of said magnetron and hermetically sealed thereto, said outer wall having an elongated passage opening into the interior of said transitional section and one of the cavity resonators of said magnetron, said passage extending axially substantially the height of said transitional wave guide section and being appreciably narrower in width than said one cavity resonator, said transitional wave guide section having a constant height in the axial direction equal to the longer cross-sectional dimension of the said rectangular wave guide and a constant width equal to the width of said passage, said transitional section being a quarter wavelength long at the operating frequency of the magnetron.

5. In a hyper-frequency energy generation system, a magnetron electron discharge device having a source of electrons, said device having a plurality of cavity resonators symmetrically disposed about an axis, a rectangular wave guide, a transitional section of wave guide of rectangular cross-section having one end connected to said rectangular wave guide and its other end abutted against the outer wall of said magnetron and hermetically sealed thereto, said outer wall having a substantially rectangular aperture opening into the interior of said transitional section and one of the cavity resonators of said magnetron, said aperture extending axially substantially the height of said cavity resonator and said transitional wave guide section and being appreciably narrower in width than said one cavity resonator, said transitional wave guide section having a constant height in the axial direction equal to the longer cross-sectional dimension of said rectangular wave guide, and having a constant width substantially equal to that of the aperture, the length of said transitional section being a quarter wavelength at the operating frequency of the magnetron, the width of said transitional section being such that said transitional section matches the impedance of said cavity resonator to the impedance of said rectangular wave guide.

6. In combination, an evacuated magnetron having a source of electrons and a plurality of cavity resonators, an output circuit for said magnetron comprising an output rectangular wave guide having a constant height and a width that is smaller than its height, and an impedance matching transformer consisting of a wave guide having a rectangular cross-section and having a constant height and a width that is smaller than its height, said transformer wave guide being coupled at one end to a cavity resonator of said magnetron and at its other end to said output wave guide, the width of said transformer wave guide at at least one end thereof being less than the width of said output wave guide.

7. The combination of claim 6, further including a window sealing one of said wave guides to retain the vacuum of said magnetron, said window being transparent to the energy propagated along said guides.

8. The combination of claim 6, wherein said transformer wave guide is tapered.

9. The combination of claim 6, wherein said transformer wave guide had a length approximately equal to a quarter of a wavelength at the operating frequency of the magnetron.

10. The circuit of claim 1, further including a window sealing one of said wave guides to retain the vacuum of said magnetron, said window being transparent to the energy propagated along said guides.

ALBERT M. CLOGSTON.
ALEXANDER G. SMITH.
